UNITED STATES PATENT OFFICE.

CHARLES LE G. FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

TRANSFORMER FOR ELECTRIC CURRENTS.

1,129,473.

Specification of Letters Patent.

Patented Feb. 23, 1915.

Original application filed August 2, 1909, Serial No. 510,854. Divided and this application filed October 8, 1910, Serial No. 586,098. Renewed August 20, 1914. Serial No. 857,773.

To all whom it may concern:

Be it known that I, CHARLES LE G. FORTESCUE, a subject of the King of Great Britain, and a resident of Pittsburgh, in the county of Allegheny and State of Pennsylvania, have invented a new and useful Improvement in Transformers for Electric Currents, of which the following is a specification, this application being a division of application Serial No. 510,854, filed August 2, 1909.

My invention relates to the windings and insulation of transformers which are adapted for use with very high-voltage circuits and it has for its object to provide a winding which is so connected and insulation which is so constructed and associated with the winding, that the manufacturing cost of the transformer and the space occupied by it may be materially reduced, while, at the same time, its terminal voltage may be very high.

In my co-pending application, Serial No. 510,854, filed August 2, 1909, of which this application is a division, I have shown and described various adaptations of insulation, composed of both insulating and conducting materials, for use with the windings of high-potential transformers.

I now desire to claim specifically one modification which is set forth and claimed broadly in said application, according to which condenser type insulation is employed, the various condenser plates being connected through resistance connections, to such points in the transformer winding as to properly fix their potential, or some other means being provided for preventing disturbances in the winding which arise from its connection to the condensers.

My invention is illustrated in the accompanying drawings, in which—

Figure 1 is a sectional elevation of a core and windings constructed and connected in accordance therewith, and Fig. 2 is a perspective view of a modified structure which also embodies my invention.

Referring to Fig. 1 of the drawings, the structure here illustrated comprises a substantially rectangular core member 1, a low-potential winding 2 that is divided into two groups of coils which surround two opposite legs 3 and 4 of the core member 1 and are separated therefrom by insulating sleeves 5,

a high-potential winding composed of two groups 6 and 7 of relatively flat coils, insulating sleeves 8 and 9 which surround the respective core legs, between the low and the high-potential windings, and insulating barriers 10 and 11 that separate the high-potential windings from each other and from the walls of a tank or casing (not shown) in which the transformer is disposed. The core legs 3 and 4 may be of any suitable form but are preferably cruciform in cross section in order to economize space and to reduce the mean length of turn in the coils.

The conducting cylinders which the insulating barriers 10 and 11 contain, are severally connected to intermediate points 70 in the transformer windings 6 and 7 through resistors 12. The connections between coils are completed through conducting strips 13, which are either embedded in insulating sleeves 8 and 9, as shown, or may be disposed between concentric insulating cylinders. By connecting the intermediate points of the winding to the conducting cylinders of the insulating barriers, through resistances, the thickness of the barriers may be 80 materially reduced, since an advantageous distribution of potential through the insulation may be maintained without danger of injuring the insulation immediately surrounding the coils, voltage disturbances produced in the plates of the condenser being 85 choked out by the resistances.

The circuit connections between coils are such as to facilitate the use of taps or connections such as those constituted by the resistors 12 between intermediate points in the winding and the condenser plates of the insulating barriers. Assuming that terminals 15 and 16 are connected to a high-potential circuit and that the middle point of the 95 winding is grounded, a circuit is established from the coil 17, through coils 19 to 48, inclusive, as indicated.

In Fig. 2, the conducting cylinders of the insulating barriers are provided with slots 100 14 which are cut alternately from opposite edges in order to form zig-zag paths for the capacity currents, thereby introducing a resistance which is non-inductive and which tends to prevent static disturbances, substantially as the external resistances 12 of Fig. 1 tend to prevent such disturbances.

The arrangement of coils and the struc-

ture may be modified within the spirit and scope of my invention.

I claim as my invention:

1. A transformer comprising a core member, a plurality of coils disposed thereon end to end, and an insulating sleeve for separating the coils from the core and comprising a set of non-conducting cylinders and a set of alternately disposed conductors, said coils being directly connected into groups of two adjacent coils each and said groups being connected together by means of said conductors to constitute a series arrangement from the middle coil groups outwardly to the end groups. 10
2. In electric apparatus, the combination with a low-potential body and a winding, of an insulating structure, comprising alternate layers of insulating and conducting materials, interposed between said body and said winding and a plurality of resistances through which the conducting layers of the insulation are joined to intermediate points in the winding. 20
3. In a transformer, the combination with a substantially rectangular core member and two groups of coils located on the respective opposite core legs, of insulating structures separating the two groups from each other and comprising concentric alternating layers of insulating and conducting materials and high-resistance connections between the conducting cylinders and intermediate points in the transformer windings. 30
4. An electrical device comprising a low-potential body, a high-potential conductor, and an insulating structure interposed between the said body and said conductor and comprising conductors embedded in insulating material, said embedded conductors having relatively high resistance to limit capacity currents therein. 35
5. In a transformer, the combination with a magnetizable core member, and a winding therefor, of an insulating structure disposed between said core member and said winding and comprising a plurality of alternate concentric cylinders of insulating and conducting materials, said conducting cylinders being provided with slots cut alternately from opposite edges to provide a zig-zag path for the capacity currents induced therein and being connected to intermediate points in the transformer winding. 50
6. In electric apparatus, the combination with a low-potential body and a high-potential conductor, of an insulating structure disposed between said body and said conductor and comprising a plurality of alternate layers of insulating and conducting mate- 60
- rials and the conducting layers being slotted to reduce the capacity currents therein. 70
7. In an electrical device, the combination with a plurality of side-by-side coils, of an insulating structure adjacent to the coils comprising spaced conductors, connections between adjacent coils, and other connections between non-adjacent coils respectively including said conductors. 75
8. In an electrical device, the combination with a plurality of side-by-side coils that are connected in a series beginning with the centrally located coils and successively including the next outermost coils, an insulating structure adjacent to the coils comprising spaced conductors, the connections between non-adjacent coils including said conductors. 80
9. In an electrical device, the combination with a plurality of side-by-side coils, of insulating structures respectively within and without the coils, each comprising alternate layers of insulating and conducting materials, connections between the coils including the conducting layers of the inner structure, and high resistance connections between the coils and the conducting layers of the outer structure. 85
10. In an electrical device, the combination with a plurality of side-by-side coils, of insulating structures respectively within and without the coils, each comprising alternate layers of insulating and conducting materials, connections between the coils including the conducting layers of one of the insulating structures, and high resistance connections between the coils and the conducting layers of the other insulating structure. 90
11. In an electrical device, the combination with two groups of side-by-side coils, of insulating structures respectively within the two groups of coils, and other insulating structures respectively outside the two groups of coils and separating the same from each other, each of said insulating structures comprising alternate layers of insulating and conducting materials, connections between the coils of each group including the conducting layers of the corresponding inner insulating structures, and high resistance connections between the coils of each group and the conducting layers of the corresponding outer insulating structures. 100

In testimony whereof, I have hereunto subscribed my name this 23rd day of Sept., 1910.

CHARLES LE G. FORTESCUE.
